VIBRATOR ROLLER FOR PRINTING PRESSES

Jesse Levine, New York, N. Y.

Application April 27, 1938, Serial No. 204,513

3 Claims. (Cl. 101—348)

This invention relates to vibrator rollers for printing presses, and particularly to those adapted for use in color printing. The object of the invention is to provide a sectional roller, preferably of all-metal construction, and composed of a plurality of sections adjustable relatively to one another, whereby printing in several colors can be simultaneously and effectively performed.

A further object of the invention is to provide means by which the various roller sections can be easily and conveniently set at any desired position relative to one another, and also means by which the entire roller can be removed as a unit from its operative position in the press.

Another object of the invention is to provide means by which the improved roller will be vibrated independently of the other rollers in the press.

In the accompanying drawing, wherein an embodiment of the invention is shown, Fig. 1 is a diagrammatic view of portions of a printing press of conventional construction, showing the relationship of the improved roller to the other rollers employed therein; Fig. 2 is a longitudinal sectional view through the improved vibrator roller; Fig. 3 is a sectional view on the line 3—3 of Fig. 2, looking in the direction of the arrows; and Fig. 4 is a sectional view on the line 4—4 of Fig. 2, looking in the direction of the arrows.

In the diagrammatic view of Fig. 1, various rollers ordinarily employed in a printing press of conventional type is shown. There, the usual ink fountain is indicated at 5, the same having the conventional partitions 6 for dividing the fountain into the chambers containing the various colored inks. The fountain is provided with the conventional doctor-blade 7, adjustable toward the distributing roller 8, which delivers a coat of ink to the roller 9, that transfers the same to the cylinder 10. Roller 11, usually of a composition material, distributes ink to the improved vibrator roller 12 from which ink is received by the rollers 13 and 14 and applied to the face of the plate 15 which makes the impression upon the paper carried over the cylinder 16. The illustration thus far given, applies to a well-known type of press, the construction of which, aside from roller 12 and associated parts, forms no part of the present invention.

The invention relates more particularly to the vibrator roller indicated at 12 and shown in detail in Figs. 2, 3 and 4. The same includes the central shaft 17 which is provided with the body portion 18. The shaft 17 is rotatably driven

driven from a source of power in the usual way. Shaft 17 is mounted at its opposite end in the bearings 19 and 20, the bearing indicated at 20 being a removable one secured in position in the arm 21 by means of the screw 22. The end portion of shaft 17 is formed with a thread 23 which turns within an internally-threaded bushing 24 held in member 25 by means of a plate spring 26 (Fig. 4), secured by the screws 27 in member 25 and extending across a portion of the periphery of the bushing 24 and resiliently resisting rotative movement of bushing 24 within member 25. A collar 28 is secured by screw 29 to bearing 20 and a screw 30 holds the member 25 in place within the collar 28.

The mechanism described serves to impart a longitudinal reciprocating movement to the roller 12 during its rotative movements, this longitudinal movement being attained by means of the thread 23 rotating within the complementary internal threads of bushing 24. Stops 31 and 32 on the shaft 17 limit the longitudinal movement of the shaft 17 in the bushing 24, the spring 26 permitting a slight resilient rotative movement of bushing 24 in its support 25 when the stop 32 contacts against stop portion 33 formed at the end of the bushing 24. A similar stop portion 34 is provided at the opposite end of bushing 24 for contact with stop 31 on shaft 17 at the proper time in the rotative movement of shaft 17.

Mounted for adjustment on the portion 18 of shaft 17 is a plurality of roller sections 35, said roller sections being adapted to be slid lengthwise on the portion 18 and fixedly yet removably positioned at any selected points thereon in any selected spaced relationship with respect to one another. The various roller sections 35 are of similar diameter and each section 35 is of sleeve-like formation and has a reduced cylindrical portion 36 at one end and an annular recess 37 at the opposite end. Thus, a reduced portion 36 on one of the members 35 will fit within the annular opening 37 of another section 35 whenever desired, so that should an occasion require it, the entire roller can be made up of a plurality of these sections 35 to form a roller surface of continuous, uniform diameter. The sections may be of various lengths, such as shown in Fig. 2, according to the area over which the ink is to be distributed by each section and they may be placed in any selected spaced relationship according to the areas of desired application of the differently colored inks.

The portion 18 of the roller shaft is formed

with a continuous longitudinally extending groove 38 intended to receive a set screw 39 threaded in and extending through, the reduced portion 36 of each of the roller sections 35. Thus, to provide a roller made up of a plurality of these sections 35, it is merely necessary to loosen the respective set screws 39 and slide the roller sections 35 along on the portion 18 and when the proper points of location have been reached, the 10 set-screws are tightened to firmly fix the roller sections 35 on the portion 18. Since the set-screws 39 will enter the groove 38, the roller sections 35 secured on the portion 18 will be held in non-rotative position relative to portion 18. 15 Since the portions 36 telescope within the recesses 37, two or more of the sections 35 may be placed together in abutment to make one long section. That is to say, the reduced portion 36 of one section 35 will enter the annular recess 37 in the 20 next section and the effect of a single roller section can be thus produced.

The roller sections 35 are preferably made of steel or other suitable metal and thus will last indefinitely in the normal use of the press. At 25 the same time, the entire roller assembly may be readily taken out of the press by removal of the bearing 20 and the shaft and assembled parts.

Through the arrangement disclosed, a very flexible means is provided for greatly facilitating 30 color printing, since the movable roller sections 35 may be located in any desired position on the length of the shaft portion 18 to apply colored areas of ink within selected portions of the printing and without overlapping. Also through this 35 device the removable roller sections are placed on the shaft only in positions corresponding to portions of the printing plate to be printed, and other parts of the shaft are left vacant, thus considerably reducing the weight of the complete 40 roller in operation and relieving strain and wear on the bearings. These and other objects are accomplished by the invention, which is not to be limited to the exact embodiment shown, but is broad enough to cover all structures coming 45 within the scope of the annexed claims.

What I claim is:

1. A sectional roller for color printing comprising, a shaft, means for mounting said shaft for rotative movement, said mounting means including a threaded portion on the shaft, a threaded bushing in which the threaded portion of the shaft is mounted, a cylindrical holder within

which the bushing is concentrically held and by which the bushing is enclosed, a bracket in which said holder is mounted, said holder having a wall portion cut away, and a flat spring disposed in the cut-away portion of the wall of the holder and 5 having its ends fixedly attached to said holder and its intermediate portion resiliently bearing against the periphery of the bushing to resiliently resist rotative movement of the same within the holder. 10

2. A sectional roller for color printing comprising, a shaft, means for mounting the shaft for rotative movement, said means including a threaded portion at one end of the shaft, a threaded bushing within which the threaded end 15 portion of the shaft is rotatable, a cylindrical holder for said bushing within which the bushing is concentrically enclosed, said holder having a cut-away portion in its annular wall to expose a portion of the bushing, a flat spring disposed across the cut-away portion of the holder and in peripheral contact with the bushing, means for fixedly securing the opposite ends of the spring in the wall of the holder, spaced stop elements on the shaft for limiting longitudinal movement of the threaded portion of the shaft in its bushing, said spring normally resisting rotative movement of the bushing within its holder and permitting slight rotative movement under resilient resistance when the stops 25 are reached during longitudinal movement of the shaft. 30

3. In a sectional roller structure for color printing, a roller means for mounting said roller for longitudinal vibratory movement comprising a 35 supporting bracket through which the shaft extends, means for detachably securing said bracket to the press frame, said bracket having a cylindrical extension, a collar concentrically fitted over and secured to said extension, a bushing 40 concentrically mounted within the collar, said bushing being internally threaded, the shaft having a threaded portion extending through the bushing and engaging with the threads therein, a sleeve secured in and projecting out of the collar, said sleeve having a slotted annular wall, and a flat spring having its ends secured to the 45 annular wall at the ends of the slot therein, said spring overlying and resiliently resisting rotative movement of the bushing within the sleeve. 50
